HYDRAULIC MACHINE

James D. Scoville, York, Pa., assignor to S. Morgan Smith Company, York, Pa., a corporation of Pennsylvania

Application November 13, 1935, Serial No. 49,457

2 Claims. (Cl. 253—143)

This invention relates to improvements in hydraulic machines of the type wherein the blades of the runner are adjustable to vary their angle and the area of the water opening through the runner to correspond with the angle and opening of the wicket gates which control the admission of water to the runner.

Heretofore, in hydraulic machines of this type, it has been customary to construct the mechanism so that when the wicket gates were operated by the governor in response to variations in the load, the adjustable blades of the runner would be correspondingly moved to thereby maintain a definite relationship between the angle or position of the wicket gates and the angle or position of the runner blades at all times.

For a given head, as the wicket gates are opened the runner blades must be opened, slowly in the lower gate range, rapidly from about 60% to 90% gate range, and slowly at the end of the gate stroke. This relationship is determined by tests and is obtained in the hydraulic machines by means of a cam in the blade control valve, said cam being operatively connected to the shaft of the wicket gates so that motion of the gates causes the blade control valve to rise or fall, which in turn causes the runner blades to open or close to their correct position.

For a given head the above referred to cam has a definite shape. However, if the head at the plant increases, the relationship between the wicket gates and the runner blades must be changed to obtain the maximum efficiency. For a given gate opening the blade angle must be larger.

An object of the present invention is to provide an improved hydraulic machine of the above type in which means are provided by which the relative positions of the runner blades with respect to the wicket gates can be quickly adjusted to obtain the maximum efficiency of the hydraulic machine when the head at the plant changes.

Another object of the invention is to provide an improved hydraulic machine of the above type in which means are provided for adjusting the cam of the runner blade operating mechanism control valve, so that the relative positions of the runner blades with respect to the wicket gates will be correspondingly adjusted to maintain such a relationship between the angle or position of the gates and the angle or position of the runner blades when the head at the plant changes that maximum efficiency will be obtained.

Another object of the invention is to provide an improved hydraulic machine of the character mentioned, which is simple in construction, and reliable and exact in function under all conditions of service.

The invention also comprises certain new and useful improvements in the construction, ar-

angement and combination of the several parts of which it is composed, as will be hereinafter more fully described and claimed.

In the accompanying drawings:

Figure 1 is a side elevation, partly in section, of a hydraulic machine employing a runner of the adjustable blade type and embodying controlling means according to the present invention, the main part of the governor being omitted so as to show the control valve device; 5

Fig. 2 is a plan of a portion of the structure shown in Fig. 1, showing the governor and control valve device; 10

Fig. 3 is an enlarged vertical section of the lower end of the runner and shaft, showing the construction of the parts within the hub of the runner; 15

Fig. 4 is an enlarged vertical section of the servo motor associated with the runner blade operating mechanism; 20

Fig. 5 is an enlarged vertical section of the oil head and associated parts on top of the generator; 25

Fig. 6 is an elevation, partly in section, of the control device as seen from the line 6—6 of Fig. 2; 25

Fig. 7 is a diagrammatic section of the control valve device, taken on the line 7—7 of Fig. 2; 30

Fig. 8 is a view similar to Fig. 6 showing the cam of the control valve device in an adjusted position; 35

Fig. 9 is an elevation of the adjustable blade runner, the blades being shown in the position assumed when the cam of the control valve device has been shifted from the position illustrated in Fig. 6 to the position shown in Fig. 8; 35

Fig. 10 is a horizontal section taken on the line 10—10 of Fig. 1 showing the wicket gates and their operating mechanism; 40

Fig. 11 is a detail plan of the adjustable rod connecting the cam of the control valve to the governor; 40

Fig. 12 is a side elevation of the structure shown in Fig. 11; 45

Fig. 13 is a section taken on the line 13—13 of Fig. 11; and 45

Fig. 14 is an enlarged view of a portion of the rod shown in Fig. 11. 50

Referring to the drawings and especially to Figs. 1, 2 and 10, the hydraulic machine may be in the form of a hydraulic turbine 11 adapted to operate an electrical generator 12, and included in the complete generating unit is a governor 13 adapted to automatically control the operation of the turbine 11, so that the turbine will operate at a substantially uniform speed, irrespective of the variations in the load. 55

The turbine 11 has a runner which is made with adjustable blades, the angular positions of which are adapted to be varied, together with the wicket gates, according to the load, so that 60

the turbine will operate at its highest efficiency at all times.

In mechanisms falling within the scope of the present invention, the operating fluid is generally oil, and the oil is supplied from the usual pressure tank (not shown) which is installed in the power house as a part of the equipment. The oil pressure tank is connected with the governor 13 and also with the runner blade operating 10 mechanism, means being provided for controlling the oil in such a manner that when the governor operates in either direction to adjust the angles of the wicket gates, the runner blades will be caused to rotate in a similar direction so as 15 to effect a corresponding adjustment in the angles or positions thereof. In this way the parts of the turbine will be simultaneously adjusted, so that all of the parts will at all times retain their correct relationship with each other, and 20 the turbine will operate with maximum efficiency and smoothness and with minimum vibration.

For the purpose of controlling the actuation of the runner blade operating mechanism, a control valve device 15 is employed. This control 25 valve is connected to the fluid pressure line and is adapted to be operated in the manner to be hereinafter described.

The turbine 11 comprises a casing 16 which forms a peripheral water inlet in which are 30 mounted an annular series of movable wicket gates 17 and stationary guide vanes 14.

Projecting from the lower end of the wicket gates 17, are trunnions 18 which are journalled in the adjacent portion of the casing 16.

35 Stems 19 project upwardly from the wicket gates 17 and terminate a suitable distance thereabove, said stems being journalled in suitable bearings carried by the casing 16.

The wicket gates 17 are adapted to be rotated 40 simultaneously into different angular positions to control the flow of water into the turbine in the usual manner, and for this purpose the upper ends of the stems 19 are provided with gate operating arms 20 which are fixed to said stems and 45 connected by links to a gate adjusting ring 21, as shown in Fig. 10.

The gate adjusting ring 21 is connected by link means 22 to a shaft 23. Fixed to the upper end of the shaft 23 is an arm 24 which is connected 50 by a link 25 in a well known manner to the controlling member (not shown) of the governor 13 (see Fig. 2).

As shown in Fig. 1 the lower portion of the turbine casing 16 forms an axially directed chamber 55 21 in which the runner 28 operates.

The hub of the runner 28 is fixed to the lower end of a hollow or tubular shaft 29 which is journalled in a suitable bearing 30 mounted in the turbine casing. The upper end of the runner 60 shaft 29 is directly connected to the shaft 31 of the generator 12 (see also Fig. 4).

Any suitable type of setting may be used for the turbine installation, a concrete setting 32 being shown in the present instance. The portion 65 of the setting below the turbine forms a draft tube 33 into which the water is discharged from the runner. The electrical generator 12 may rest on top of the setting as shown in Fig. 1.

Referring now to Fig. 3, the hub of the runner 70 28 is bolted or otherwise fixed to the lower end of the runner shaft 29.

A suitable number of blades 34 are rotatably supported in the hub of the runner 28 and project radially therefrom. In the present instance 75 four blades are shown (see also Figs. 1 and 10).

The inner end of each blade 34 is formed with a trunnion 35 which is journalled in bearings 36 and 37 supported in the hub. The construction is such that the blades are rotatable into different angular relationships with the axis of the 5 runner.

Means are provided for simultaneously rotating all of the blades 34 and for maintaining them in equal angular relationship, such means comprising preferably an arm 38 rigidly fixed on the trunnion 35 of each blade, and links 39 which pivotally connect the arms on the different blades to a cross head 40. The cross head 40 is guided to reciprocate in a direction axially of the runner by guide pins 41, which are mounted in the hub of the runner in the manner shown in Fig. 10. It will be understood that the relative positions of the blades 34 govern the area of the water passages or openings between the blades, and that when the blades are rotated, the area of the water passages is increased or decreased depending upon the direction in which the blades are moved.

As shown in Figs. 1, 3 and 9, a cap 42 is bolted or otherwise removably secured to the lower end 25 of the hub of the runner 28. Since the hub of the runner is otherwise enclosed and the hub is hollow, the cap 42 provides a closed chamber or reservoir for containing a supply of grease for lubricating the various working parts of the 30 mechanism contained within the hub of the runner.

The cross head 40 is bolted or otherwise fixed to the lower end of an operating rod 43 which extends upwardly through the hollow runner 35 shaft 29.

As shown in Fig. 4 the upper end of the operating rod 43 is fixed to the piston 44 of a servo motor 45 which is mounted in the runner shaft 29 adjacent to the point where the runner shaft is joined 40 to the generator shaft 31.

The servo motor piston 44 is contained in a cylinder which may be formed as an enlargement of the runner shaft 29, the upper portion of said cylinder being closed by the lower portion of the 45 generator shaft 31, as shown in Fig. 4.

The upper portion of the operating rod 43 passes through a bushing 46 mounted in the runner shaft 29, and this bushing besides forming a bearing for the operating rod 43, provides 50 means for closing the chamber 47 on the lower side of the piston 44.

The servo motor piston 44 is double acting, and in order to supply oil to both sides thereof for the purpose of operating the same in either direction, 55 two tubes or pipes 48 and 49 are employed. The pipes 48 and 49 are mounted within the hollow generator shaft 31 and rotate therewith, said pipes extending from the servo motor upwardly through the shaft 31 to a head 50 which is mounted on top of the generator 12 (see Figs. 1 and 5). If so desired the pipe 49 can be concentrically disposed within the pipe 48.

The lower end of the pipe 49 is in communication with the chamber 47 on the lower side of the 65 servo motor piston 44 and the lower end of the pipe 48 is in communication with chamber 51 on the upper side of said piston.

The lower end of the pipe 49 is fixed to a cap 52 carried by the servo motor piston 44, and therefore the pipe 49 will be moved rectilinearly in the generator shaft 31 when the servo motor operates. A chamber 53 is provided within the cap 52, said chamber being connected to the piston chamber 47 by means of passages or ports 54 formed in the 75

piston 44, so that oil supplied through the pipe 49 will flow into the chamber 47.

The lower end of the pipe 48 terminates above the cap 52, so as to be in communication with the chamber 51 of the servo motor. The lower end of the pipe 48 may be secured to the lower end of the generator shaft 31, by means of a member 55 having a peripheral flange which is bolted or otherwise secured to the adjacent portion of the generator shaft 31. The member 55 provides means for closing the lower end of the hollow generator shaft 31 and thereby cut off communication from the chamber 51 to the space within said shaft exteriorly of the pipes 48 and 49.

15 Referring now to Fig. 5, the head 50 is formed with a plurality of superposed cavities 56, 57, 58 and 59, the cavities 57 and 58 constituting chambers for containing oil, and the cavities 56 and 59 forming housings for the mechanism.

20 The upper end of the pipe 48 terminates within the chamber 58 so that said chamber is at all times in communication with the servo motor chamber 51. For the purpose of securing the upper end of the pipe 48 in position, a member 60 is employed. This member has a peripheral flange which is bolted or otherwise secured to the adjacent portion of the body of the head 50. In order to prevent leakage of oil from the chamber 58 into the cavity 59, a packing gland 61 is fitted 25 to the member 60 and surrounds the pipe 48.

25 The pipe 49 projects upwardly through the chambers 58 and 57, and terminates in the cavity 56. For the purpose of guiding the pipe 49, a bearing 62 is fitted in the wall separating the 30 chambers 57 and 58. Since the bearing 62 snugly fits around the pipe 49, leakage of oil between the chambers 57 and 58 is reduced to a minimum.

35 The top of the chamber 57 is closed by means of a cap plate 63 which is detachably secured to the head 50 by means of bolts or other suitable fastening means. A packing gland 64 is secured to the cap plate 63 and surrounds the upper portion of the pipe 49 so as to seal the top of the chamber 57.

40 A plurality of openings 65 are formed in the portion of the pipe 49 which is located within the chamber 57, so that oil can flow from said chamber into the pipe and from thence downwardly to the chamber 47.

45 At a convenient point in the cavity 59, the pipe 48 has fixed thereto a sealing ring 66. This sealing ring is associated with a pan 67 carried by the upper portion of the generator 12 in such a manner that any oil seeping through the packing gland 61 will be prevented from passing down the exterior of the pipe 48 to the upper end of the generator shaft 31. In order to prevent oil from 50 accumulating in the pan 67, the bottom of the pan is perforated, as at 68 (Fig. 5), near the outer edge thereof, so that the oil will pass to the outside of the upper end of the generator shaft 31.

55 The upper end of the pipe 49 is closed by a plug 69. The plug projects upwardly into the cavity 56. The upper portion of the plug 69 is hollowed out to form a recess 70.

60 Mounted on a shaft 73 which is transversely disposed in the upper portion of the head 50, is a lever 72, and depending from said lever is an arm 71 which extends into the recess 70 in the plug 69. A ball 74 is interposed between the end of the arm 71 and a bearing block 75 in the bottom of the recess 70. The construction and arrangement of these parts is such that vertical movement of the pipe 49 in either direction is 65 transmitted through the arm 71 and lever 72 to

the shaft 73, with the result that the shaft will be rotated in either direction. It will also be understood that due to the provision of the ball 74, a universal joint is formed between the pipe 49 and arm 71, so that the pipe 49 will be free 5 to rotate with respect to the non-rotating arm 71, during the operation of the turbine.

Referring now to Figs. 6, 7 and 8, the control valve device 15 comprises a casing formed with a cylinder 86. Contained in the cylinder 86 is 10 a valve 87. As shown, the cylinder and valve may be vertically disposed, and the valve has a stem 88 which projects upwardly through the top of the casing of the valve device 15.

A plurality of ports 91, 92, 93, 94 and 95 are 15 provided for connecting the cylinder 86 with a plurality of chambers 96, 97, 98, 99 and 100 respectively. The valve 87 is formed with a pair of spaced apart and connected heads 89 and 90. The ports 92 and 94 are spaced apart a suitable 20 distance, so that the heads 89 and 90 will lap said ports when the valve 87 is in one position, as will be hereinafter described, and all of the ports are so disposed relatively to each other, that when the valve 87 is in certain other positions said ports will be connected in the manner to be hereinafter described.

25 Chamber 97 is connected by a pipe 101, with the chamber 58 in the head 50, and a pipe 102 connects chambers 98 and 57 (see Figs. 5 and 7). 30 The chamber 98 is connected to the oil pressure conduit 103, by a pipe 104, which is fitted with a manually operated valve 105. (See Figs. 2 and 7.)

35 Chambers 96 and 100 are connected by a pipe 106 to the return conduit 107 which connects the governor 13 with the sump tank (not shown) of the oil pressure system (see Figs. 2 and 7).

40 For the purpose of operating the valve 87, a cam 108 is provided. This cam comprises an elongated body which is mounted for horizontal movement in a slot 131 formed in a saddle 109. The saddle 109 is bolted or otherwise attached to the side of the casing of the control valve device 15, as shown in Figs. 6 and 7. 45

45 One end of the cam 108 is connected by a link or rod 110, to an arm 111 fixed to and projecting from the gate operating shaft 23, so that rotation of the shaft 23 resulting from the operation of the governor 13, results in the cam being 50 moved rectilinearly in the saddle 109 (see Fig. 2).

55 As shown in Figs. 6 and 8, the upper surface of the cam 108 is formed with a cam face 112 which is adapted to engage a roller 113, carried by a vertically movable plunger 114. The plunger 114 is mounted in a bore 132 formed in the saddle 109.

60 The upper end of the plunger 114 is formed with a threaded portion 126 which passes through an opening 127 formed in a bracket 128. Above 60 the bracket 128, the threaded portion 126 has nuts 129 and a washer 130 mounted thereon so as to provide means for manually raising the plunger 114, should it be so desired.

65 The bottom of the plunger 114 is formed with an enlarged portion 115, which constitutes a weight for maintaining the roller 113 in contact with the cam face.

A pair of bars 117, which are arranged in parallel relation on opposite sides of the valve stem 70 75 88 and plunger 114, have one end pivotally connected, as at 118, to the plunger 114, their intermediate portion pivoted to the valve stem 88, as indicated at 119, and their other end connected by a link 120, to one arm of a bell crank lever 75

- 121, the link 120 being connected to the bars 117 by means of a pivot pin 124 (see also Fig. 1). The bars 117 constitute a floating lever, the purpose of which will be hereinafter described.

5 The bell crank lever 121 is supported by a bracket 122 mounted on the base of the apparatus, as shown in Figs. 1 and 2. The other arm of the lever 121 is connected by a rod 123 to an arm 125 fixed to the shaft 73.

10 It will be understood that when the parts are operatively assembled and the chambers 51 and 47 are charged with oil under pressure, the weight of the parts connecting the floating lever 117 and the arm 125 will pull the lever 72 downwardly, thereby maintaining the free end of the arm 71 in engagement with the ball 74, so that any movement of the pipe 49 will be transmitted through the levers and links hereinbefore described to the floating lever 117.

15 As shown in Figs. 2, 11, 12, 13 and 14, the link or rod 110 is so made that its length can be changed, so that the position of cam 108 with respect to saddle 109 of control valve device 15 can be shifted or adjusted for the purpose to be 20 hereinafter described.

25 The link or rod 110 is formed with an elongated portion 140, one end of which is formed with an eye 141 through which is inserted a pivot pin 142 carried by a bracket on the outer 30 end of the cam 108. The opposite end of portion 140 is formed with left hand threads 143.

35 The opposite end of the link or rod 110 is preferably made in the form of a yoke 144 having two arms which straddle the end portion of arm 40 111 of the governor shaft 23, said yoke being pivotally connected to said arm by means of a pin 145, as shown in Fig. 2.

45 The yoke 144 is formed with an internally threaded portion having right hand threads 146 (see Fig. 13). Engaging the threads 146 is an 50 end of a threaded rod 147 which is mounted in the yoke 144 and projects outwardly therefrom.

55 For the purpose of connecting portion 140 of rod 110 with the yoke 144, use is made of an elongated nut 148, the threaded bore of which is formed with right hand threads for engaging the threaded portion 143 of portion 140 and left hand threads for engaging the rod 147. Nut 148 is formed with a plurality of openings 149 so that 60 the nut can be turned by means of a suitable tool (not shown) having prongs adapted to be inserted in said openings.

65 In order that the parts of the link or rod 110 may be locked in an adjusted position, lock nuts 150, 151 and 152 are provided, nut 150 being mounted on the threaded portion 143 of rod 140 and being adapted to engage the adjacent end wall of nut 148, nut 151 being mounted on rod 147 for engagement with the adjacent end wall 60 of nut 148, and nut 152 being mounted on rod 147 for engagement with the end of yoke 144. Threaded rod 147 is held in position in the yoke 144 by means of a set screw 153.

70 The above described construction of the link or rod 110 constitutes a turnbuckle arrangement by means of which the length of the link or rod 110 can be adjusted to suit varying conditions, and in order that an operator or power house attendant can readily observe the adjustment of the link or rod 110, suitable indicating means are provided. Such indicating means may comprise, as shown in Figs. 11 and 12, an indicator arm 154 having one end fixed to the yoke 144 and its opposite or free end made in the form of a pointer 75 155, and a series of notches 156, 157 and 158 formed on the rod 140 and adapted to cooperate with said pointer. Any number of notches may be employed. In the instant case, three notches are shown, and the intermediate notch 156 is so formed on the rod 140 that when the pointer 155 is disposed adjacent thereto the link or rod 110 will have such length that the cam 108 will be positioned in the control valve device 15 at the correct position for the normal head for which the apparatus is designed. Notch 157 may be for a lower, and notch 158 for a higher head, as will be hereinafter described.

80 In operation, when the governor 13 operates to swing the wicket gates 11 toward open or closed position to vary the gate opening to conform with variations in the load on the turbine, the rotation of the shaft 23 in either direction will effect a corresponding movement of the valve 81 of the control valve device 15, since said valve is connected to the governor through the floating lever 117, plunger 114, cam 108, link 110, and arm 111, and the servo motor 45 will be supplied with fluid under pressure so as to operate the runner blade operating mechanism toward open or closed position.

85 In Figs. 1 and 10, the runner blades 34 are shown approximately one-half opened and the governor and wicket gates are shown correspondingly positioned. With the runner blades 34 opened approximately one-half, the cam 108 of the control valve device 15 is so positioned that the roller 113 engages the cam face 112 at a point approximately equi-distant from the highest and lowest points thereof, so that the plunger 114 is maintained correspondingly positioned 90 within the frame provided by the saddle 109 (see also Figs. 6 and 7).

95 When the governor 13 and control valve device 15 are inactive, the valve 81 is so positioned in the cylinder 86, that the valve heads 89 and 90 lap the ports 92 and 94, respectively. With the valve 81 in this position, communication is cut off between the cylinder 86 and the chambers 97 and 99, respectively, and oil under pressure is retained or bottled up in chambers 51 and 58, pipes 48 and 49, and chambers 51 and 47, respectively, so that the servo motor piston 44 remains in a position corresponding to the position of the runner blades 34. The parts will remain so positioned until the governor 13 operates, in response to a variation in load, to shift the wicket gates 11.

100 As shown by the arrow in Fig. 2, the governor 13 moves toward the left to close the wicket gates and toward the right to open said gates.

105 The cam 108 is connected to the gate shaft 23 in such a manner that movement of the governor 13 in one direction, causes the cam to move in the opposite direction. That is to say, when the governor moves toward the left (Fig. 2), the cam 108 is moved toward the right (Fig. 6) and vice versa, when the governor moves toward the right, the cam 108 moves toward the left.

110 Should the load on the turbine decrease, the governor 13 will act to move the wicket gates 11 toward closed position, so as to decrease the quantity of the driving fluid supplied to operate the runner 28.

115 The movement of the governor toward the left causes a corresponding movement of the cam 108 toward the right, with the result that the plunger 114 moves downwardly. The downward movement of the plunger 114 is effective through the floating lever 117, and said lever is swung downwardly on the fulcrum provided by the pivot pin 124, and this action causes a downward move-

ment of the valve 87, so that the valve heads 89 and 90 uncover the ports 92 and 94, respectively.

When the valve 87 moves downwardly and port 92 is uncovered, chamber 97 is connected to chamber 96, through port 92, chamber 133, and port 94, and fluid under pressure is vented from the servo motor chamber 51 to the return conduit 107, through pipe 48, chamber 58, pipe 101, chamber 97, port 92, chamber 133, port 94, chamber 96 and pipe 106.

Simultaneously with the venting of fluid under pressure from the chamber 51, fluid under pressure is supplied to the chamber 47 of the servo motor 45, from the supply pipe 103, through pipe 104, chamber 98, port 93, valve chamber 134, port 94, chamber 99, pipe 102, chamber 51 and pipe 49.

The fluid under pressure thus supplied to the chamber 47 acts on the underside of the servo motor piston 44 and forces said piston upwardly. This upward movement of the piston 44 is transmitted by the rod 43 to the cross head 40, and said cross head acting through the links 39 and arms 38, will simultaneously rotate the runner blades about their trunnions as axes, toward closed position.

Since the shaft 73 is connected to the servo motor piston 44 by means of the lever 72, arm 71, and the pipe 49, said shaft will be rotated in a clockwise direction as soon as the servo motor piston 44 commences to move upwardly to effect a change in the angle or position of the runner blades.

The rotation of the shaft 73 is transmitted by the arm 125, rod 123, bell crank 121 and link 120, to the left hand end of the floating lever 117 (Fig. 7), and said lever will accordingly be swung upwardly about the fulcrum provided by the pivot pin 118. In this action of the floating lever 117, the valve 87 will be raised slightly, thereby moving the valve 87 toward lap position. However, the upward movement of the valve 87 is counteracted by the continued downward movement of the plunger 114, so that while the left end of the lever 117 is gradually raised, the right end of said lever will be gradually lowered. In this way the valve 87 will be maintained in the position in which the ports 92 and 94 are respectively uncovered by the valve heads 89 and 90 an amount sufficient to establish communication in the above described manner to both sides of the servo motor piston 44.

The movement of the right end of the floating lever 117 is definitely limited by the governor 13, but the opposite or left end of said lever will continue to move as long as the ports 92 and 94 are not lapped by the heads 89 and 90, respectively, of the valve 87. Therefore, the left end of the floating lever 117 will continue its upward motion until the ports 92 and 94 are lapped, thereby cutting off the communication through which fluid under pressure is supplied to operate the servo motor 45.

The action of the governor 13 will continue until the wicket gates have been closed an amount sufficient to cause an overload on the turbine, whereupon the governor reverses and moves the wicket gates toward open position, thereby gradually relieving the load on the turbine.

Since the rotation of the runner blades as effected by the servo motor 45, is not simultaneous with the action of the governor 13, but closely follows the same, the upward movement of the plunger 114 resulting from the reversed action of the governor, taken in connection with the movement of the servo motor piston 44, will,

through the action of the floating lever 117, cause the valve 87 to move to the position in which the ports 92 and 94 are lapped. In this way the communication through which fluid under pressure is supplied to operate the servo motor piston 44 is cut off and the operation of the servo motor is interrupted. The runner blades will then have been brought to an angle or position corresponding with the adjusted position into which the wicket gates have been brought by the governor 13.

The parts will then remain so positioned relative to each other until the wicket gates are again operated, whereupon a runner blade adjusting operation similar to that just described will again take place to automatically move the runner blades into proper position with respect to the position assumed by the wicket gates.

However, when the load is increased, the governor 13 will move in the direction opposite to that shown by the arrow in Fig. 2 and the operation of the other parts will be reversed to that heretofore described. In this connection it will be noted that the valve 87 moves upwardly in the cylinder 86, so that when the port 94 is uncovered, chambers 99 and 100 will be connected, and chambers 97 and 98 will be connected. Fluid under pressure will then be vented from the servo motor piston chamber 47 and fluid under pressure will be supplied to the servo motor piston chamber 51, so that the piston 44 will be moved downwardly.

The extreme positions of the floating lever 117 are shown by broken lines in Fig. 7. When the runner blade adjusting mechanism is inactive and the runner blades are approximately one-half opened, the floating lever 117 will be in an approximately horizontal position, as shown. When the runner blades are closed, the floating lever 117 will be in the position shown by the broken lines indicated at A (Fig. 7), and when the runner blades are opened wide, the floating lever will be in the position shown by the broken lines indicated at B (Fig. 7).

As above described, under a predetermined head the adjustable runner blades of a hydraulic turbine are opened or closed to conform with the opening or closing of the wicket gates by the usual governor to maintain the speed of the turbine constant under increases or decreases in the load, so that the runner blades may always occupy an angle or position which corresponds with a definite position of the wicket gates as determined by the output of the turbine.

However, if the head at the plant increases or decreases, the relationship between the relative positions of the wicket gates 17 and the runner blades 34 should be changed to obtain the maximum efficiency.

For instance, if the head increases, for a given gate opening, the blade angle must be larger.

Heretofore, when the head at plant changed this has been taken care of by removing cam 108 and installing in place thereof another cam having a different cam surface for engaging roller 113. But this method has proven unsatisfactory on many occasions, due to the fact that cams were not available to suit the change in head. That is to say, when the operating head was half way between the points for which the cams were designed, there was an unavoidable loss in efficiency when one cam was substituted for another.

Therefore, in order to provide means whereby the relative position of the cam 108 can be readily shifted in accordance with variations in the

operating head at a plant, it is proposed to shift the position of the cam in the control valve device by lengthening or shortening the link or rod 110 which connects the cam with the govern- 5 nor arm 111.

In Fig. 6 the broken line indicating cam surface 112 is in the same position as the full line of said cam surface shown in Fig. 8, and the broken line indicating cam surface 112 in Fig. 8 10 is the same as the full line of the cam surface shown in Fig. 6. This shifting of the position of cam 108 may be easily effected by unscrewing lock nuts 150 and 151 and then rotating nut 148 to shorten the link 110.

15 Thus, assuming that the normal head at a plant is 35 feet (see Fig. 11), and the head increases to 40 feet, the above described method of shortening the link 110 can be quickly effected and when the indicator 155 registers with the 20 notch 158 (40 foot mark on rod), the operator will have correctly shortened the link 110 to take care of the change in head at the plant.

When the link 110 is thus shortened and cam 108 moved toward the left (Figs. 6 and 8), 25 plunger 114 will, through the engagement of roller 113 with the cam surface 112, be moved upwardly in the bore 132 of the saddle 109.

The upward movement of the plunger 114 will effect an upward swinging movement of the 30 floating lever 117 on the fulcrum provided by the pivot pin 124, and this action causes an upward movement of the valve 87, so that the valve heads 89 and 90 uncover the ports 92 and 94, respectively.

35 When the valve 87 moves upwardly and ports 92 and 94 are uncovered, chamber 97 is connected to chamber 98, and chamber 99 is connected to chamber 100. Fluid under pressure will then be vented from the servo motor piston 40 chamber 47, through ports 54, chamber 53, pipe 49, ports 65, chamber 57, pipe 102, chambers 99 and 100 to pipe 106, and fluid under pressure will be supplied to servo motor piston chamber 51, from pipe 104, through chambers 98 and 97, 45 pipe 101, chamber 58, and pipe 48, so that the piston 44 will be moved downwardly. This downward movement of servo motor piston 44 is transmitted by the rod 43 to the cross head 40, and said cross head acting through the links 39 50 and arms 38, will simultaneously rotate the runner blades 34 about their trunnions as axes, so that the runner blades are shifted from the dotted line position shown in Fig. 9, which dotted line position it will be noted corresponds to the 55 full line position, Fig. 1, in which the runner blades have a position corresponding to the one-half opened position of the wicket gates (see also Fig. 10) toward the full line position, Fig. 9.

As the governor 13 is inactive during this adjustment in position of the runner blades, no change in position will be imparted to the wicket gates 17, as will be understood.

Since shaft 73 is connected to the servo motor piston 44 by means of the lever 72, arm 71, and pipe 49, said shaft will be rotated in a counter-clockwise direction as soon as the servo motor piston 44 commences to move downwardly. This rotation of shaft 73 is transmitted by arm 125, rod 123, bell crank 121 and link 120, to the left 60 hand end of the floating lever 117 (Fig. 7) and said lever will accordingly be swung downwardly about the fulcrum provided by the pivot pin 118. In this action of the floating lever 117, the valve

87 will be lowered until ports 92 and 94 are lapped, thereby cutting off the communication through which fluid under pressure is supplied to operate the servo motor 45. The runner blades will then have been moved to the full line position shown in Fig. 9, from the position indicated by the broken lines, which full line position corresponds with the adjusted position of cam 108. 5

In this way the relative positions of the runner blades with respect to the wicket gates can be 10 altered to suit variations in head, so that when the head on the turbine changes, the turbine will operate at the maximum efficiency.

It will be understood that when the head on the plant decreases the cam 108 can be shifted 15 in the opposite direction, which action will effect a corresponding adjustment of the runner blades in the opposite direction so that under variations in head in either direction the adjusted positions of the runner blades with respect to 20 the wicket gates can be altered so that under all conditions the turbine will operate at the maximum efficiency.

While one illustrative embodiment of the invention has been described in detail, it is not 25 my intention to limit its scope to that embodiment or otherwise than by the terms of the appended claims.

Having thus described my invention what I 30 claim is:—

1. In a turbine, a runner having blades and means for adjusting the blades into different angular positions, gates and means for adjusting the gates into different angular positions, a governor, mechanism operated by the governor for 35 controlling the operation of the gate adjusting means, means separate from said mechanism operated by the governor for controlling the runner blade adjusting means, means for adjusting said controlling means, a rod connecting the 40 governor with said controlling means, and means for changing the length of said rod whereby the adjustment of said controlling means is changed in accordance with variations in head on the runner. 45

2. The combination with a runner having blades adjustable into different angular positions, and gates adjustable into different angular positions and controlling the flow of the driving fluid to the runner, of a governor for adjusting 50 the angular positions of the gates, fluid pressure operating means for adjusting the positions of the runner blades, means for maintaining the relative positions of the runner blades in synchronization with the gates, comprising a valve 55 device for controlling the supply of fluid under pressure to said runner blade adjusting means, a cam for actuating said control valve device, a rod connecting said cam with said governor whereby operation of said governor simultaneously effects operation of said cam so that the runner blades will be adjusted in accordance with changes in position imparted to the gates by the governor, and means for changing the length of 60 said rod whereby the position of said cam with respect to said valve device is changed in accordance with variations in head on the runner so that the relative positions of the runner blades with respect to the wicket gates are changed in order that the runner will operate at the maximum efficiency. 70

JAMES D. SCOVILLE.
